UNITED STATES PATENT OFFICE.

WILLIAM H. DOBLE, OF QUINCY, AND SAMUEL B. FIELD, OF HOLBROOK, MASSACHUSETTS, ASSIGNORS OF ONE-FOURTH TO PNEUMATIC SCALE CORPORATION, LIMITED, A CORPORATION OF MAINE, AND THREE-FOURTHS TO SAID DOBLE.

FOLDING BOX OR SHIPPING-CASE.

1,699,847.

Specification of Letters Patent.

Patented June 9, 1914.

Application filed March 7, 1913. Serial No. 752,593.

To all whom it may concern:

Be it known that we, WILLIAM H. DOBLE and SAMUEL B. FIELD, citizens of the United States, residing at Quincy, county of Norfolk, State of Massachusetts, and Holbrook, county of Norfolk, State of Massachusetts, respectively, have invented a certain new and useful Improvement in Folding Boxes or Shipping-Cases, of which the following is a specification, reference being had therein to the accompanying drawings.

The special object of the invention is to provide a folding box of sufficient size and strength to serve as a shipping case in which goods may be packed for shipping, and the goods be protected against damage by breaking of the case while being handled, and which can be folded into small compass to be returned to the shipper.

The invention is an improvement upon the invention of Patent No. 941,013 to Doble and Wheaton, Nov. 23, 1909.

The box of the present invention is of rectangular form, having six panels comprising a bottom, two sides, two ends, and a top or cover, which are adapted to be hinged together. The six panels of the box are formed with an inner and an outer wall spaced apart from each other, and preferably having corrugated strengthening plates in the space between the walls, the panels thus formed being all hinged together by hinge pins, part of which are fixed or stationary and part of which are removable. When it is collapsed it will be somewhat similar in effect to the collapsing of an ordinary paper carton.

The invention will be fully understood from the following description taken in connection with the accompanying drawings, and the novel features will be pointed out and clearly defined in the claims at the close of the specification.

In the drawings, Figure 1 is a perspective view of a box constructed in accordance with the invention, the cover being closed and sealed. Fig. 2 is a vertical section through the front and back of the box shown in Fig. 1, and showing in dotted lines the way that the bottom is folded up against the front and the way that the top is folded over against the back after the locking rods are withdrawn and the box is collapsed. Fig. 3 is a horizontal section of the closed box, and

showing in dotted lines the way that one end folds against the inner face of the back and the other end folds against the inner face of the front when the box is collapsed.

For convenience of designation the six sides or panels of the box will be referred to respectively as the front, the back, the two ends, the cover, and the bottom. Referring now to the drawings, the six panels referred to are the front A, the back B, the left and right-hand ends C and D respectively, the cover E and the bottom F. The front A is hinged to the bottom F and to the two ends C and D by fixed hinges and the top E is hinged to the back B by fixed hinges, while the front A has a separable hinge connection with the top E and the back B has a separable hinge connection with the bottom F. By removing the front hinge pin between the top and the front the top or cover can be turned back so as to open the box and by also pulling out the hinge pin between the back and the bottom and folding the top over against the outer face of the back and folding the bottom up against the outer face of the front, then by pushing the front slightly in the right-hand direction, as viewed in Fig. 1, and pushing the back toward the left-hand, as shown in Fig. 1, the entire box may be collapsed into flattened form.

The front A has a double wall composed of the outer plate 1 and the inner plate 2. The back B has an inner plate 3 and an outer plate 4. The end C has an outer plate 5 and an inner plate 6. The end D has an outer plate 7 and an inner plate 8. The cover E has an outer plate 9 and an inner plate 10, and the bottom F has an outer plate 11 and an inner plate 12. The corrugated plates between the walls are substantially alike and are represented by the numeral 13.

The lower side of the front A is provided with a series of knuckles 14 to receive a hinge pin 15, and the bottom F is provided with a series of knuckles 16 to receive a hinge pin 17. These knuckles 14 and 16 should be of equal length and the spaces between the knuckles 14 and the spaces between the knuckles 16 should be of equal length and against each other. The rods 15 and 17 are connected together at the spaces between the knuckles 16—16 by links 18 which may

be described as in the form of a double barrel sleeve, the two barrels of the sleeve being connected by a neck portion 19, one barrel of the sleeve being adapted for the passage 5 of the hinge pin 15 and the other barrel of the sleeve being adapted to receive the pin 17. These hinge pins pass loosely through these sleeves so that the links may be turned on either one of the pins 15-17.

10 The knuckles 14 are preferably made of sheet metal which is bent so as to form not only the knuckle itself but to form a hollow or box shank or tang portion 20 of just the right thickness to squeeze in between the 15 inner and outer walls 1 and 2 of the front, and to form a contracted neck between the shank and the knuckle. The knuckles 16 are also similarly formed with a neck and a shank portion 21 adapted to fit into the 20 space between the walls 11 and 12 of the bottom F. These shank portions 20 and 21 should be firmly secured within the respective walls with which they are engaged so that they will remain permanently in place. 25 This may be done in any suitable way, either by a tight driving fit or by welding or by positive fastening means, if desired.

The top or cover E has a hinge connection with the back B in a similar way to the 30 hinge connection just described of the front A with the bottom F, the top E being provided with the knuckles 22 secured thereto by the shank portions 23 and the back B being provided with the knuckles 24 secured 35 thereto by the shank portions 25, said knuckle portions receiving respectively the pins 26, 27 which are connected together intermediate the knuckle portions by the links 28 having a connecting neck portion 29.

40 The front A has a hinge connection with the left-hand end C by means of the series of knuckle portions 30 which engage with the end wall C and a series of alternating knuckle portions 31 which engage with the 45 front A, these knuckles 30 and 31 respectively being formed with a box shank which engages with the space between the walls of the end and front respectively in the same manner as described with reference to the 50 knuckle portions 14 and 16. A hinge pin 32 fits fast within the knuckles 31 which are connected with the front A, but the hinge pin 32 fits loosely in the knuckles 30 connected with the end C so that said end C 55 may be swung around on said hinge pin.

The knuckles 30 are formed with a box shank or tang 33 similar to the box shanks previously described in connection with the other knuckles, and preferably formed with 60 a contracted neck 34 so as to allow clearance for the swinging around of the walls on the hinges, so that the ends of the walls will not interfere with each other. The knuckle 31 is formed with a box shank or tang 35 65 and with a contracted neck similar to the

construction described for the knuckles 30. As in the folding of the box the rear edge of the left-hand end C is to be swung toward the left, as viewed in Figs. 1 and 3, so that the end C will come into alinement with the 70 front A the right-hand end D should swing to the left, as viewed in Figs. 1 and 3, against the face of the front A. For this reason the form of the hinge which connects the front A with the end D must contain 75 an off-set. Therefore, the knuckle 36 is formed with a neck 37 and a shank or tang 38 bent at right angles to the neck 37, so that the said shank 38 enters the space between the walls of the end D, the neck 37 80 being of sufficient length so that when the end D is swung around on the hinge pin 39 which passes through the knuckles 36 there will be a sufficient clearance to allow the end 85 38 to swing around into parallel relation with the front A against the inner face thereof. The knuckles 40 having straight-a-way shanks 41 are connected with the front A in the spaces between the knuckles 36, the hinge pin 39 being fast within said knuckles 90 40 so that the hinge or swinging connection is through the swinging knuckles 36. The rear edge of the right-hand end D is connected with the right-hand end of the back B by means of a hinge pin 42 engaging with 95 knuckles 43, and the knuckles 44 alternate with the knuckles 43, said knuckles 43 having shank portions 45 which engage with the space between the walls of the back B and the knuckles 44 having shank 46 which engages with the space between the walls of 100 the end D. The hinge pin 42 is made fast to one set of knuckles and is loose in the other set of knuckles so that in the folding of the box the back B and the end D may 105 be brought into alinement with each other and folded down flat against the front A and end C.

The left-hand end of the back B is connected with the edge of the left-hand end C 110 in a similar manner and by a similar form of hinge construction to that by which the front A is connected with the end D, namely, a knuckle 47 has a neck 48 and a box shank 49 at right angles with said neck, said shank 115 49 engaging firmly within the space between the walls of the end C and a series of knuckles 50 in the space between the knuckles 47 having shanks 51 which engage within the spaces of the back B and a hinge pin 120 52 which is fast within the knuckles passes loosely through the knuckles 47.

The bottom F has a separable hinge connection with the back B as follows: A series of knuckles 53 are formed with shanks 54 125 and intermediate connecting neck portions similar to those already described for some of the other knuckles, said shanks 54 engaging in the space between the walls of the bottom F, being firmly secured therein, and 130

8 a series of knuckles 55, alternating with the knuckles 53, are formed with shanks 56 which fit between the walls of the back B, being fast therein. A pin 57 passes loosely 6 through both sets of knuckles so that when in position it locks the bottom and the back together. This pin 57 is formed with a head 10 on one end, not shown, but similar to the head 65 on the locking pin 64 which connects the top E with the front A. This pin 57 is adapted to be pushed in through the knuckles 53 and 55, the head of said pin forming a stop to prevent its being shoved too far in and the other end of the pin is so 15 constructed that a seal or locking device of some sort may be attached after the pin is inserted to prevent a withdrawal of the pin without first opening the lock or breaking the seal. In the drawings this locking arrangement is shown as a wire 58 which passes through a transverse hole in the projecting portion of the locking pin and bent to form a loop, the ends of said wire being secured together by a seal 59. In order to 20 withdraw the locking pin the seal has to be broken.

The front A has a separable locking pin connection with the top E in a similar manner to that in which the back B is connected 25 with the bottom F,—namely, the upper edge of the front A is provided with a series of knuckles 60 having box shanks 61 which engage between the walls of the front A and a series of knuckles 62 alternating with the 30 knuckles 60 have shanks 63 which engage between the walls of the top E. The locking pin 64 is adapted to engage with said knuckles 60 and 62 by an endwise movement and is provided with head 65 at one end, the 35 other end having a lock or seal similar to that employed with the locking pin 57, namely a wire 66 which passes through a hole transversely through the rod 64 and a seal 67 which secures the two ends of the 40 wire together.

The left-hand ends of the top E, the back B, and the bottom F extend flush up against the face of the left-hand end C and the right-hand ends of the top E, the back B, and the bottom F extend flush up against 45 the face of the right-hand end D.

Now, after the box has been set up, filled, and sealed, as in Fig. 1, if it is desired simply to inspect the contents of the box or to 50 open the box for removal of a portion of the contents, the seal 67 will be broken so that the locking pin 64 can be withdrawn and then the top E can be turned back on its hinge, as shown in dotted lines in Fig. 2, 55 said top E serving in such case as a hinge cover and such portion of the contents, as desired, can be removed and then the cover closed, and if desired the locking pin can be reinserted and resealed or not, as desired.

60 After the contents have been entirely re-

moved, and it is desired to knock down or fold the case for shipping or for compact stowing away, the locking pin 57 will be removed after breaking the seal 59, the locking pin 64 also being removed. Then the top E 65 will be folded over and down onto the back side of the back B, and the bottom F will be folded up against the outside of the front A, as shown in dotted lines in Fig. 2. Then by a diagonal pressure the front A and the left-hand end C will be straightened out in alignment with each other and the back B and the right-hand end D will be straightened out into alignment with each other, the end D lying upon the inner face of the front A 70 and the back B lying against the inner face of the left-hand end C, as shown in dotted lines in Fig. 3.

What we claim is:

1. In a folding box, having hinged panels, 85 one of two adjacent panels having a hinge with a shank secured thereto, said shank being formed with a right-angled bend terminating in eyes extending at right angles with the panel and spaced apart from 90 each other, said adjacent panel having eyes extending from the edge adjacent to said first panel and spaced apart from each other in such manner that said eyes will enter the spaces between the eyes of said first panel, 95 and a hinge pin passing through the interlocking eyes of both of said panels whereby one of said panels may be laid over flat and parallel with the other of said panels.

2. A knockdown metallic box having six 100 panels which form four sides, a top and a bottom, each panel having an inner and an outer wall with space between the two walls, hinges connecting some of the panels, said hinges having a box shank portion of folded 105 metal integral with the knuckle of the hinge, said shank portion entering the space between the inner and outer walls of the panels, and engaging with the inner faces of 110 said walls and hinge pins engaging with the knuckle portions of the hinges.

3. A knock down metallic box having panels formed with inner and outer walls with spaces between the walls, hinge connections between two panels, said hinges consisting of metal bent to form a knuckle and a hollow shank integral with the knuckle, the hollow shank entering the space between the walls and engaging with the inner faces 115 of said walls.

4. A knock down metallic box having six panels which form four sides, a top and a bottom, each panel having an inner and an outer wall, hinge connections between the panels whereby all of the panels are hinged 125 together, some of the panels having hinges formed with shanks having a right angle bend whereby when the box is knocked down or collapsed, one panel may be turned over flat against the face of an adjoining panel. 130

5. A box having a hinge connection between two adjacent panels thereof, each of said two panels having a series of tubular bearings at intervals apart from each other 5 projecting from the adjacent edges thereof opposite to and parallel with each other, a separate shaft extending through the said bearings of each of said panels, at least one set of said bearings being loose on its shaft, 10 and links which connect said shafts in the intervals between said bearings, said links having two parallel series of eyes through which respectively both of said shafts pass loosely, the links being rotatable on at least 15 one of said shafts as a center, the other shaft being rotatable within the eye portions of said links through which it passes, thereby permitting one of said panels to be swung around into a plane parallel with the other 20 of said panels.

6. In a box having two adjacent panels each of which has a series of knuckle bearings spaced apart from each other and formed with shanks secured to the adjacent 25 edges of said panels whereby the said bearings project from the edge of the panel, the bearings which project from one panel lying parallel with and equal in length to the bearings on the other panel, a separate shaft extending through each set of bearings, at least 30 one set of said bearings being loose on its shaft, and links which connect said shafts in the intervals between said bearings, said links having two parallel series of eyes 35 through which respectively both of said shafts pass loosely, the links being rotatable on at least one of said shafts as a center, the other shaft being rotatable within the eye portions of said links through which it 40 passes, thereby permitting one of said pan-

els to be swung around into a plane parallel with the other of said panels.

7. A box having panels consisting of inner and outer walls spaced apart from each other, two adjacent panels of which each 45 have a series of knuckle bearings spaced apart from each other and formed with shanks which engage in the space between the inner and outer walls and project outward therefrom, the bearings which project 50 from one panel lying parallel with the bearings which project from said adjacent panel, a separate shaft extending through each set of bearings, at least one of said bearings being loose on its shaft, and a series of links 55 which connect the two shafts at the intervals between said bearings and are rotatable on at least one of said shafts as a center, thereby permitting one of said panels to be swung around into a plane parallel with the other 60 of said panels.

8. A box having panels formed of inner and outer walls spaced apart from each other, two adjacent panels being hinged together, the hinges consisting of bent plates 65 forming knuckles with parallel end portions forming a shank, said shank portion being inserted and secured between the inner and outer walls, the knuckle portions of one panel fitting between the knuckle portions of 70 the adjacent panel, and a hinge pin passing through the knuckles.

In testimony whereof we affix our signatures, in presence of two witnesses.
